UNITED STATES PATENT OFFICE.

ALBERT T. WEISS, OF ROCHESTER, NEW YORK, ASSIGNOR TO YAWMAN & ERBE MANUFACTURING COMPANY, OF ROCHESTER, NEW YORK, A CORPORATION OF NEW YORK.

LABEL-HOLDER FOR LABELING-MACHINES.

1,153,144.

Specification of Letters Patent.

Patented Sept. 7, 1915.

Original application filed August 1, 1910, Serial No. 574,872. Divided and this application filed October 9, 1911. Serial No. 653,463.

To all whom it may concern:

Be it known that I, ALBERT T. WEISS, of Rochester, in the county of Monroe and State of New York, have invented certain new and useful Improvements in Label-Holders for Labeling-Machines; and I do hereby declare the following to be a full, clear, and exact description of the same, reference being had to the accompanying drawings, forming a part of this specification, and to the reference numerals marked thereon.

My present invention relates to labeling machines and more particularly to machines of the type disclosed in my prior application, Serial No. 574,872, filed August 1st, 1910, of which this is a division, and it has for its object to provide a simple, efficient and durable label holder that will produce a uniform feed and offer certain advantages in the way of adjustments and conveniences for the operator.

A further object of the invention is to provide an improved automatic feeding device for presenting the labels at the delivery end of the holder as the pile becomes diminished.

To these and other ends the invention consists in certain improvements and combinations of parts all as will be hereinafter more fully described, the novel features being pointed out in the claims at the end of the specification.

In the drawings, Figure 1 is a side elevation of a portion of a labeling machine and of a label holder, constructed in accordance with and illustrating one embodiment of my invention; Fig. 2 is a detail top plan view, much enlarged, of the label holder taken partly in section on the line 2-2 of Fig. 1; Fig. 3 is a front elevation; Fig. 4 is a detail section through the label holding boxes, taken on the line 4-4 of Fig. 2, and Fig. 5 is a rear elevation.

Similar reference numerals throughout the several figures indicate the same parts.

To first briefly outline the general nature of the labeling machine in connection with which I have, in the present instance, shown the device of my invention combined, reference will be had more particularly to Figs. 1 and 2 in which—

1, 2, 3 and 4 illustrate uprights constitut-

ing parts of the main frame of the labeling machine. A swinging picker 5 is employed in the latter, pivoted at 6 and operated by a connecting rod 7 and as it moves between the label holders to be hereinafter described and its delivery point, it is supplied on its picking faces 8 and 9 with adhesive by a distributing roller 10 vibrated on a pivot 11 by a connecting rod 12 so that it contacts alternately with the picker faces and the feed roll 13 of an adhesive receptacle 13a.

The machine is adapted for the simultaneous application of two labels, such as the neck and body labels of a bottle, and hence two label boxes 14 and 15 are provided, preferably in rear of the uprights 1 and 2. In the present instance they are both carried on a table or support 16 having a limited movement from front to rear of the machine on a centrally disposed guide 17 projecting forwardly from the rear standards 3 and 4, and flanked on either side by 75 brackets 18 forming extended guiding abutments. The table has an adjustable bearing against the abutments to a limited degree as it turns on its supporting guide 17 in the plane of the labels through the medium of 80 set screws or other suitable adjustable stops 19, extending therethrough and contacting with the upper faces of the brackets. In this way adjustment of the label holder laterally of the path of the picker is effected 85 to improve the alinement between the two when necessary.

The label boxes themselves may be of any suitable construction, but are preferably divided so that the piles of labels may be inserted edgewise from the top of the machine into one-half after the other half or removable portion has been detached. In the present instance the body label box 15 comprises a lower half 20 and an upper half 21, 95 the former being secured at 22 in a forward position on the table 16, and the latter being held in co-operative relation therewith by a thumb screw 23 permitting their detachment from each other. Each is fitted with suitable guide stakes 24 that may be constructed and arranged in the same manner as the guide stakes 25 on the neck label holder shown in detail in Fig. 4, each stake being provided with a supporting arm 26 that is 105 held under a screw or clamping device 27

that allows the adjustment of the stake for different sets of labels varying slightly as to size. The forward ends of the stakes, or at least a proportion of them, have inwardly turned toes 28 that normally prevent the advanced labels of the pile from being forced out of the box by the follower devices hereinafter described, but permitting the removal of the labels one at a time by the adhesive contact of the picker 8 in a manner well known in the art. The upper or, in the present instance, neck label holding box 14, is also composed of a lower part 29 and an upper part 30, held against it by a suitable catch device 31 or otherwise, the lower part being secured at 32 in a forward position on a supplementary table 33 overhanging the body label box 15. The table 33 is in turn mounted on pins or standards 34 rising from the table 16 in rear of the lower label box, and is preferably removable to permit ready access to the latter.

It is sometimes desired to interrupt the label feed to the picker without at the same time preventing the operation of the various other mechanisms, as for instance, during adjustments or tuning up of the parts, say, when the paste pot has just been filled and the various paste transferring devices have not run sufficiently long to become properly coated. It is for this purpose that the label holder table 16 is given its limited horizontal front and rear movement on the guide 17 and the bearing surfaces 18, such movement being effected in the present instance by a pair of draw bars 35 fixed to a rock shaft 36 journaled in the table at 37. The draw bars extend forwardly at each side of the main frame to terminate in laterally extending handle portions 38 and are provided with locking projections 39 that coöperate with lateral stops or projections 40 on the front uprights 1 and 2 to lock the label holder in its forward position. In this position the picker can engage the piles of labels, but when the draw bars are raised by the operator and the label holder pushed back, the range of upward and backward movement of the picker is too limited for it to reach the labels at all, and hence while it passes through its picking movement as usual the latter is rendered ineffective.

In view of the fact that the neck label picking surface 9 of the picker 5 is in a different plane from the body label picking surface 8 thereof and advanced with respect thereto in the direction of downward movement of the picker, for the purpose of conforming approximately to the contour of a bottle, the neck label box 14 is arranged in a position slightly forwardly of the body label box 15 so that the bottom or foremost label of its pile is presented a little in advance of that of the other, and the picker is enabled to detach both labels simultaneously

and exert approximately an equal pressure against both piles in so doing.

The means I employ in the present instance for urging the piles of labels toward those ends of the boxes from which they are detached by the picker, and for resisting or backing up the intermittent pressure of the latter as well as compensating for the depletion of the piles themselves are practically the same for each label box, and a description of one will suffice for both. Referring more particularly therefore to Figs. 2, 4 and 5 of the drawings, illustrating the neck label holder in detail, a bracket 41 arranged centrally in rear of the label box 14 offers a guide 42 for a follower rod 43 that is preferably disconnected from but bears loosely against a follower plate 44, preferably through the medium of a yielding element, such as a leaf spring 45, interposed between the two. The follower plate operates in the box and engages the top or rear ends of the pile of labels. A shaft 46 journaled in the bracket 41 is fitted with an arm 47 having a weight 48 adjustable thereon to normally operate a second arm 49 in a direction causing a link 50 pivoted thereto at 51 and to the follower rod 43 at 52, to operate the rod against the follower plate and labels. To prevent a retrograde movement of the follower device and labels under the contact of the pickers, the rod 43 is provided with teeth 53 with which coöperate a pair of pawls 54 pivoted at 55 to the bracket or guide 41—42, and held by gravity in normal engagement therewith. These pawls, or at least their engaging portions, are so spaced and arranged with respect to the spacing of the teeth 53 on the follower rod that one is in operative engagement with a tooth at the time the other is in a position between the two teeth, and thus without making the latter so fine as to jeopardize their strength or the dependability of their engagement, the rod is locked without an appreciable degree of lost movement by actuation thereof through a distance equal to less than the distance between two teeth. Stop pins 56 on the pawls limit the gravity actuated movements thereof into the guide to prevent them from impeding the insertion of the follower rod or the initial adjustment of the latter against the labels, and also lock the pawls to resist the strain of their engagement with the rod. When it is desired to lock the follower in a retracted position, as for instance while a pile of labels is being inserted in the box, a catch 57, pivoted at 58 to the table, is swung up to engage the arm 49 and maintain it and the weighted arm 47 in elevated positions.

I claim as my invention:

1. In a label holder for bottle labeling machines, the combination with a table or support, of a body label box mounted there-

on to sustain labels in a horizontal pile, said box being made in separable halves divided horizontally so that the upper half may be lifted off to permit the pile of labels to be inserted edgewise, a detachable label box, and means for supporting the latter independently of the body label box and in a position overhanging the latter.

2. In a label holder for bottle labeling machines, the combination with a table or support, of a body label box mounted thereon to sustain labels in a horizontal pile, a standard arranged on the table at one side of the box and independently of the supporting means for the latter, a bracket on the standard, and a neck label box carried on the bracket independently of the body label box to overhang the latter, the neck label box being independently detachable and each box being made in separable halves divided horizontally so that the upper half may be lifted off to permit the pile of labels to be inserted edgewise.

3. In a label holder for bottle labeling machines, the combination with a table or support, of a body label box mounted there-

on to sustain labels in a horizontal pile, standards arranged to rise from the table on opposite sides of the box and independently of the supporting means for the latter, a bracket on the standards spanning the box, and a neck label box carried by the bracket independently of the body label box to overhang the latter, the neck label box being made in separable halves divided horizontally so that the upper half may be lifted off to permit the pile of labels to be inserted edgewise.

4. A label holder for labeling machines comprising a support, a label box thereon, a bracket on the support having a guide therein, a follower provided with a stem or rod movable in the guide to bear against the pile of labels, a lever journaled on the bracket having one of its arms weighted and a link connected to the other arm and to the follower.
